UNITED STATES PATENT OFFICE

90,554

DESIGN FOR A LAMP SHADE

Eugene Schwarz, Alexandria, Ind., assignor to
The Mantle Lamp Company of America,
Chicago, Ill., a Corporation of Illinois

Application June 19, 1933. Serial No. 48,456

Term of patent 3½ years

To all whom it may concern:

Be it known that I, EUGENE SCHWARZ, a citizen of the United States, residing at Alexandria, in the county of Madison and State of Indiana, have invented a new, original, and ornamental Design for Lamp Shade, of which the following is a specification, reference being had to the accompanying drawing, forming a part thereof.

Fig. 1 is a plan of a frusto-conical lamp shade, which has been opened up or developed, showing my new design, and

Fig. 2 is a diagrammatic view showing the outlines of the shade when assembled.

I claim:

The ornamental design for a lamp shade, as shown.

In testimony whereof, I affix my signature.

EUGENE SCHWARZ.
